Garrison Smith and Henry Brown, of Philadelphia, Pa.

Assignees to:

J. B. Raymond, G. L. Bartell and W. H. Hobin, of Philadelphia, Pa.

Letters Patent No. 42116; Dated July 12th 1864.

Design for a Stove.

The schedule referred to in these Letters Patent and making part of the same.

Shell whom it may concern:

Be it known that we Garrison Smith and Henry Brown, of the City and County of Philadelphia and State of Pennsylvania, have invented a new and original design for a stove, and we do hereby declare that the following is a full, clear and exact description thereof, reference being had to the accompanying drawings, making a part of this specification, in which:

Figure 1, is a perspective view showing the front part of the base of the stove.

Figure 2, is a perspective view representing an ornamental ring which is intended to fit on top of the stove cylinder.

Figure 3, is the design for the stove top.

Our design relates to that class of stoves known as a upright cylinder stove and refers particularly to those portions of such a stove known as the cap, the ring, and the base. The base of the stove is quadrangular, having a hearth, a, the design of which represents a shell having scalloped edges. The upright front face, b, of this base portion represents an ornamented moulding or inverted cyma reversa. The top plate, c, of this base is foliated as represented in figure 1.

The ring, figure 2, is ornamented with a head, d, surrounded by an open work border, e.

DES. 1968

2

The top of the stove is conical and surrounded by a
finial, at the base of which is a net or openwork, surrounding which
is a concave foliated design, which has a supertine openwork border
as shown in figure 3.

Having described my invention, what I claim as new
and desire to secure by letters Patent is

The design for the base, the ring and the cap of a stove
represented respectively by the figures 1, 2 and 3.
